UNITED STATES PATENT OFFICE

167,428

AUTOMOBILE BUMPER

David E. Scott, Detroit, Mich., assignor to Chrysler Corporation, Highland Park, Mich., a corporation of Delaware

Application September 7, 1951, Serial No. 16,549

Term of patent 7 years

(Cl. D14—6)

To all whom it may concern:

Be it known that I, David E. Scott, a citizen of the United States, residing in the city of Detroit, county of Wayne, and State of Michigan, have invented a new, original, and ornamental Design for an Automobile Bumper, of which the following is a specification, reference being had to the accompanying drawing, forming part thereof, in which:

Fig. 1 is a front elevational view of an automobile bumper, showing my new design;

Fig. 2 is a top plan view thereof;

Fig. 3 is an end elevation of the bumper;

Figs. 4 and 5 are vertical sections taken on the lines 4—4 and 5—5 of Fig. 1; and

Fig. 6 is a vertical section taken on the line line 6—6 of Fig. 3.

I claim:

The ornamental design for an automobile bumper, substantially as shown.

DAVID E. SCOTT.
